CLAIM

The ornamental design for a microwave oven, as shown and described.

DESCRIPTION

FIG 1 is a top, front and right side perspective view of a microwave oven showing our new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevational view thereof;

FIG. 7 is a bottom plan view thereof.

The black areas shown in FIGS. 1-3 and 6 are understood to represent the color black.

FIG. 1

FIG. 2

FIG. 3

FIG. 4

FIG. 5

FIG. 6

FIG. 7
